HIGH INTENSITY MULTIPLE AUTOMATIC
ARC LAMP

Frederick A. Berg, Chicago, Ill.

Application February 3, 1930, Serial No. 425,440

17 Claims. (Cl. 176—51)

This invention relates to an improved high intensity multiple automatic arc lamp, particularly adapted for motion picture projection, whereby a high efficiency is obtained from the source of light and passed through the film at great concentration for better projection work.

This application constitutes a companion case to application Serial No. 412,309, filed December 7, 1929, for "Multiple high intensity hydraulic projection lamp machine", and one of the main objects of the present invention is to provide a still more efficient and readily operated device.

Still another important object of this invention is the provision in a projection lamp machine for motion picture work of a plurality of elliptical mirrors for gathering the light rays from a pair of arcs or sources of light positioned at the focal points of one of the mirrors, the carbons and the accompanying apparatus being positioned and supported in such a way that undesirable shadows and light obstruction is eliminated.

Another and still further important object of the invention is the provision, in an arc lamp for motion picture work, of means for readily removing and replacing carbons when burned out or broken, which means may, if necessary, be utilized while the machine is actually in operation.

Still another important object of the invention is the provision, in a motion picture projection lamp, of automatic means for directing the arc and feeding the carbons for the arcs, this automatic means being augmented by manually operated arc striking and feed means for both positive and negative carbons.

Other and further important objects of the invention will be apparent from the disclosures in the accompanying drawings and following specification.

The invention, in a preferred form, is illustrated in the drawings and hereinafter more fully described.

In the drawings:

Figure 1 is a side elevation of the improved projection apparatus of this invention, parts being broken away to show the interior thereof.

Figure 2 is an enlarged side elevation of the tubular support for the carbons, which tubular support extends through a suitable opening provided therefor in the center of one of the elliptical mirrors.

Figure 3 is a top plan view of the tubular support with the carbons positioned thereon.

Figure 4 is a rear view of the combination automatic and manually operated arc striking de-

vice and also of the automatic feed for the carbons.

Figure 5 is a sectional view of the means for instantly positioning and releasing the negative carbons, this view being taken on the broken line 5—5 of Figure 3, looking in the direction indicated by the arrows.

Figure 6 is a side elevation of the outer end of the tubular carbon support illustrating the positioning and supporting of the positive carbons, and being in effect an extension of Figure 2.

Figure 7 is a top plan view of the apparatus shown in Figure 6, parts being broken away and shown in section, this figure being in effect an extension of Figure 3.

Figure 8 is a detail sectional view of one side of the construction shown in Figure 6, the section being taken on the broken line 8—8 of Figure 6, and looking in the direction indicated by the arrows.

Figure 9 is a sectional view taken on the line 9—9 of Figure 8, looking in the direction indicated by the arrows.

Figure 10 is a sectional view of the line 10—10 of Figure 6, looking in the direction indicated and showing the operation of the carbon clamping elements in dotted lines.

Figure 11 is a detail side view of the reflecting prism for inspecting the arcs.

Figure 12 is a transverse view through a portion of the casing shown in Figure 1 and illustrating particularly the elliptical shape of the mirrors.

As shown in the drawings:

The reference numeral 10 indicates generally the casing of the improved motion projection machine of this invention, having a multiple arc therein composed of positive carbons 12 and 13 and negative carbons 14 and 15 respectively.

In order that the multiple arcs will function properly, the reflecting mirrors are made concave and elliptical as illustrated at 16 and 17 respectively, each of the arcs being positioned at one of the foci of the smaller mirror, the construction of the mirrors themselves and the hydraulic cooling thereof being more particularly illustrated in the companion case as identified above. The outlet and inlet pipes for the cooling water are shown in Figure 1.

In the present invention, one of the particular objects is to so support the carbons for the arcs and the arc striking and carbon feeding mechanism that there will be a minimum of interference between the light rays emanating from the arcs and the mirrors themselves so that a greater

lighting efficiency will result and a consequent maximum concentration of light through the film aperture 18 will be effected.

The actual support for the carbons and their appurtenances comprises a steel tube or the like 19, the same being suitably covered with asbestos or other insulating material as best shown at 20. This tube is positioned by means of a plate 21 and bolts 22 upon the rear wall 23 of the casing which rear wall is also lined with suitable insulating material 24, the wall itself being mounted so as to be readily slidably rearwardly on the rods 25 (Figure 1) mounted in the ball-bearing supports 26 whereby the entire equipment may be withdrawn rearwardly from the housing 10 for the purpose of repairs, replacements, adjustments or the like.

Positioned immediately above the supporting tube 19 is a pair of negative carbon feed screws 27 (Figures 2 and 3) which are operated in the usual manner through 28 connected to a motor drive or the like whereby a positive forward feed of the carbons is accomplished to compensate for the burning away of the material during the operation.

A solenoid 29 is provided, the same being electrically connected to the current carrying wires 30 for the negative carbons whereby the throwing in of the switch for the current will automatically 30 shift the screws 27 and the related carbons 14 and 15 forwardly, thereby striking the arcs. This is accomplished by means of a magnetic rod 30 extending rearwardly from the solenoid, the same being pivotally connected to a lever 31, the lower 35 half of which lever is broken and then hinged together at 32 whereby the downwardly extending bifurcated ends 33 may be pushed forward manually to complete the striking of the arc in the event that the solenoid does not function. This manual forward push is accomplished 40 against the pressure of a helical spring 34 positioned against a washer 34a at the forward ends of the screws 27 whereby the carbons will be automatically returned to proper operating position 45 as soon as the arc is established.

Extending forwardly through the tube 19 is a pair of drive shafts 35 which have driving gears 36 positioned on their rear ends, these gears being likewise motor driven from any convenient 50 source of power preferably through motor driven gears 31, a similar set of gears 31a operating the gears 28, the rotation of the shafts 35 imparting a corresponding feed to the positive carbons 12 and 13 respectively. Current carrying wires for the positive carbons are illustrated at 38, (Figures 2 and 6), these being connected to current-carrying rods 39 which are carefully insulated from the remainder of the apparatus.

In the event that a manual adjustment of the feed for either the positive or negative carbons is desired, hand wheels 40 are provided mounted on the shafts 41 which shafts also carry the gears 42, these shafts being slidable for a short distance in and out of the wall 23 whereby a rearward motion thereof will cause the gear 42 to mesh with the gears 28 whereby the position of the negative carbons may be adjusted independently of the automatic operation thereof, and a slight forward movement of the hand wheel and shaft will cause the gear 42 to mesh with the gears 36 whereby a manual adjustment of the position of the positive carbons can be accomplished.

It will be noted that the shafts 35 extend forwardly through the tube 19 to approximately the

end thereof, and adjacent their outer ends, are fitted with fiber or mica gears 43, (Figures 7 and 10), which insulate the shafts 35 at this point from any further portion of the apparatus, each of the gears 42 in turn meshing with a pair of drive gears 44, these gears 44 being integral with knurled duplex carbon feed rollers 45. These gear and feed roller elements are mounted on shafts 46 suitably supported in ball bearings 47 whereby consequent ease of operation is accomplished regardless of heating of these bearings which very often occurs owing to the amount of current carried through the carbon electrodes 12 and 13. Suitable complementary rollers 48 are provided, these rollers also having their outer faces knurled to provide a gripping contact with the carbons, and it will be noted that these rollers are likewise mounted in antifriction bearings 49.

The positive carbons 12 and 13 are positioned at a slight angle with respect to the tube 19, as in this way less of the light rays will be interfered with, and the bearing faces of the feed rollers 45 and 48 are formed in accordance with this angular positioning of the carbons so that a correct spiral feeding thereof will result, and this feed will be more positive on account of the fact that a full bearing surface is provided between the feed rollers and the adjacent surfaces of the carbons.

In order that the carbons themselves may be conveniently and readily removed and replaced when exhausted or broken an instantaneously operated gripping and release means is provided, this being illustrated in detail in Figure 5 for the negative carbons and in detail in Figure 10 for the positive carbons.

In Figure 5 is shown a spring-operated clamp for each of the carbons, this comprising a co-ordinated pair of gripping elements 50 and 51, the elements 50 being fixed and forming part of the support, and the elements 51 being pivotally mounted at 52 to the portions 50. A coiled spring 53 is provided at each pivotal mounting point so that the movable elements are forwardly impelled into carbon gripping position as shown in the full lines in Figure 5. A socket 54 is provided in the top of each movable element 51 into which an operating pin 55 or the like may be inserted whereby the element may be forced outwardly against the tension of the spring 53, thereby immediately releasing the carbon for removal and replacement.

It will be noted that the mounting for these negative carbons includes a plurality of set screws 56 positioned in each supporting member 57 whereby the alignment of the carbons themselves with respect to the remainder of the apparatus and to the positive carbons may be accurately adjusted.

It will be noted that the combination supporting, releasing and gripping means for the negative carbons are movable as a whole and fed forwardly along with the carbons by means of the feed screws 27, being carefully insulated, however, from the feed screws by means of double layers of mica or other insulating material as best illustrated at 58 in Figure 2. The adjacent set screws 56 are also carefully insulated, being positioned in the sockets 59 composed of insulating material.

The quick release and mounting mechanism for the positive carbons (Figure 10) is somewhat similar to that for the negative electrodes, this mounting, however, including the spiral rotating

feed mechanism as heretofore described, the co-operating feed rollers 48 being mounted in the shiftable housing 60 which is movable outwardly to release the carbons, this also being normally maintained in carbon gripping position by means of a coiled spring 61 and operated by means of a pin 62 which can be inserted into a socket 63 adjacent the bottom of the movable portion of the casing.

The current carrying connections for the positive carbons (Figures 6 to 8) consist of electrodes 64 and 64a composed of nickel or some other non-corrodible alloy or metal which closely contact with the carbons 12 and 13, each of the electrodes 64 having a socket 65 formed in the rear face thereof into which projects a pin 66, the pin being mounted in the movable portion 60 of the carbon gripping and feeding mechanism. It will be noted that the pin 66 is carefully covered with insulating material 67 so that no current will be carried from the electrodes 64 to the carbon feed mechanism or its associated parts. These electrodes are forced into carbon gripping position by means of coil springs 68 as best shown in Figure 6. Thus, the action of the elements 60 and 64 is unitary.

In order that the positive carbons may be kept properly aligned, thereby insuring a proper operation of the arc, a support is provided for the rearwardly extending ends thereof, this support comprising a pair of bracket members 70 (Figure 9) fastened to but insulated from the tube 19, each of the bracket members 70 having mounted therein set screws 71 whereby the relation of the carbons with respect to the brackets and with respect to the feed and gripping elements and the electrodes may be accurately determined. It will be noted that the tubing at this point includes ball bearings 72 for the outer ends of the shafts 35, these bearing elements being carefully insulated from the interior of the tubing by means of a layer of mica or the like 73.

Allowance is made for inaccuracies and inequalities in diameters of the carbons, particularly with respect to the relationship between the gripping and feed members 60 and the current-carrying electrodes 64 by so positioning the pin 66 in the opening 65 in the electrode 64 that the pin will have considerable lost motion in the larger opening 65 whereby a positive contact between the electrode 64 and the carbon 13 will be effected regardless of any differences in diameter between the carbons at this point and at the point where the feeding and gripping elements contact therewith. It will be noted that the electrodes 64 and their appurtenances are carefully insulated from the supporting shaft 19 by means of layers of mica or the like 74.

A ventilating motor and fan 75 is provided in the top of the casing 11, this being regulated and controlled by a damper 76 and a clean-out tube 77 is also provided adjacent the motor and fan whereby the interior of the casing may be conveniently cleaned, this portion of the device, however, having been described in more detail in the companion case as heretofore described.

Mounted in the top of the housing 10 is a pair of reflecting prisms 78, one on each side thereof whereby the condition of the arcs may be readily inspected at all times, each of the prisms being triangular in cross-section as illustrated, and having its rear face 79 silvered to form a reflecting surface whereby the light rays are directed outwardly to the observer's eye. Pivotal points 80 are provided at the sides of the prisms so that

they can be readily tilted, thereby affording the opportunity for proper and instantaneous adjustment of the prism itself with respect to the relation between the observer's eye and the arc. A quadrant-shaped housing 81 in each prism is provided so that the same is capable of being readily tilted, a pivotal point 80 being frictionally mounted so that the desired positioning of the reflecting prism will be always maintained. A shelf 82 is provided for supporting the motor for driving the gear wheels, and the solenoid 29 is held in position by means of a strap 83.

It will be evident that herein is provided a high intensity automatically operated multiple arc lamp for motion picture projection work which, in addition to providing an amount of available light far in excess of that produced by present devices, will have included therein an automatically operated manually augmented feed for the carbons together with simple yet efficient adjustments therefor, while at the same time providing for a practically instantaneous removal and replacement of one or both of the carbons, it being possible to immediately replace one carbon while the machine is being operated from light produced by the other set of carbons. Further, the device either automatically or manually compensates for irregularities in the carbons themselves and is so constructed as to eliminate overheating of the bearings and consequent undesirable sticking of the feed mechanism.

I am aware that many changes may be made, and numerous details of construction varied throughout a wide range without departing from the principles of this invention, and I, therefore, do not purpose limiting the patent granted hereon otherwise than as necessitated by the prior art.

I claim as my invention:

1. A multiple high intensity arc including an elliptical reflecting focusing mirror, the arcs being positioned at the focal points of the mirror and mounted on a support projecting through an opening in the center of the mirror, said support comprising a tube and carbon supporting and feed means mounted in conjunction with the tube, the negative carbon feed positioned outside the tube and the positive carbon feed drive extending inside the tube to the outer end thereof.

2. A multiple high intensity arc including an oval rimmed elliptical reflecting focusing mirror, the arcs being positioned at the focal points of the mirror and mounted on a support projecting through an opening in the center of the mirror, said support comprising a tube and carbon supporting and feed means mounted in conjunction with the tube, the negative carbon feed positioned outside the tube and the positive carbon feed drive extending inside the tube to the outer end thereof, the negative feed connected with a quick release gripping means for the carbons.

3. A multiple high intensity arc including an oval rimmed elliptical reflecting focusing mirror, the arcs being positioned at the focal points of the mirror and mounted on a support projecting through an opening in the center of the mirror, said support comprising a tube and carbon supporting and feed means mounted in conjunction with the tube, the negative carbon feed positioned outside the tube and the positive carbon feed drive extending inside the tube to the outer end thereof, the positive feed including a quick release gripping means for the carbons.

4. A multiple high intensity arc including a concave reflecting focusing mirror, the arcs being positioned at the focal points of the mirror

and mounted on a support projecting through an opening in the center of the mirror, said support comprising a tube and carbon supporting and feed means mounted in conjunction with the 5 tube, the negative carbon feed positioned outside the tube and the positive carbon feed drive extending inside the tube to the outer end thereof, the positive feed including a quick release gripping means for the carbons, and also including 10 gripping electrodes for the carbons.

5. A multiple high intensity arc including an elliptical reflecting focusing mirror, the arcs being positioned at the focal points of the mirror and mounted on a support projecting through an
15 opening in the center of the mirror, said support comprising a tube and carbon supporting and feed means mounted in conjunction with the tube, the negative carbon feed positioned outside the tube and the positive carbon feed drive extending
20 inside the tube to the outer end thereof, together with a manual feed adjustment for the carbons.

25 with a manual feed adjustment for the carbons.
30 6. A multiple high intensity arc including an elliptical reflecting focusing mirror, the arcs being positioned at the two focal points of the mirror and mounted on a support projecting through an opening in the center of the mirror, said support comprising a tube and carbon supporting and feed means mounted in conjunction with the tube, the negative carbon feed positioned outside the tube and the positive carbon feed drive extending inside the tube to the outer end thereof, the negative feed connected with a quick release gripping means for the carbons, together with an individual manual feed adjustment for both sets of carbons.
35

7. A multiple high intensity arc including an elliptical reflecting focusing mirror, the arcs being positioned at the focal points of the mirror and mounted on a support projecting through
40 an opening in the center of the mirror, said support comprising a tube and carbon supporting and feed means mounted in conjunction with the tube, the negative carbon feed positioned outside the tube and the positive carbon feed drive extending inside the tube to the outer
45 end thereof, the negative feed connected with a quick release gripping means for the carbons, together with an individual manual feed adjustment for the carbons, said feed adjustment comprising a hand wheel and gears, said gears
50 being shiftable into meshing relation with the feed gears for either the positive or negative carbons.

55 8. A multiple high intensity arc including an elliptical reflecting focusing mirror, the arcs being positioned at the focal points of the mirror and mounted on a support projecting through an opening in the center of the mirror, said support comprising a tube and carbon supporting and feed means mounted in conjunction with the tube, the negative carbon feed positioned outside the tube and the positive carbon feed drive extending inside the tube to the outer end thereof, and automatic means for striking the arc between the carbons.

60

65

9. A multiple high intensity arc including an elliptical reflecting focusing mirror, the arcs being positioned at the focal points of the mirror and mounted on a support projecting through an opening in the center of the mirror, said support comprising a tube and carbon supporting and feed means mounted in conjunction with the tube, the negative carbon feed positioned outside the tube and the positive carbon feed drive extending inside the tube to the outer end

thereof, and automatic means for striking the arc between the carbons, said automatic means including a solenoid in the current carrying circuit for the arcs.

10. A multiple high intensity arc including an elliptical reflecting focusing mirror, the arcs being positioned at the focal points of the mirror and mounted on a support projecting through an opening in the center of the mirror, said support comprising a tube and carbon supporting and feed means mounted in conjunction with the tube, the negative carbon feed positioned outside the tube and the positive carbon feed drive extending inside the tube to the outer end thereof, and automatic means for striking the arc between the carbons, said automatic means including a solenoid in the current carrying circuit for the arcs, and a system of levers connected with the solenoid for feeding the negative carbons forwardly into contact with the positive carbons upon closing of said circuit. 5 10 15 20

11. A multiple high intensity arc including an elliptical reflecting focusing mirror, the arcs being positioned at the focal points of the mirror and mounted on a support projecting through an opening in the center of the mirror, said support comprising a tube and carbon supporting and feed means mounted in conjunction with the tube, the negative carbon feed positioned outside the tube and the positive carbon feed drive extending inside the tube to the outer end thereof, and automatic means for striking the arc between the carbons, said automatic means including a solenoid in the current carrying circuit for the arcs, and a system of levers connected with the solenoid for feeding the negative carbons forwardly into contact with the positive carbons upon closing of said circuit, and a manually operated arc striking element in conjunction with said automatically operated mechanism. 40

12. A multiple high intensity arc projector including an elliptical reflecting focusing mirror, the arcs including carbons positioned at the focal points of the mirror and mounted on a support projecting through an opening in the center of the mirror, said support comprising a tube and carbon supporting and feed means mounted in conjunction with the tube, the negative carbon feed positioned outside the tube and the positive carbon feed drive extending inside the tube to the outer end thereof, and automatic means for striking the arc between the carbons, said automatic means including a solenoid in the current carrying circuit for the arcs, and a system of levers connected with the solenoid for feeding the negative carbons forwardly into contact with the positive carbons upon closing of said circuit, and a manually operated arc striking element supplementing said automatically operated mechanism, said manually-operated arc striking element comprising a hinged connection in the solenoidally operated lever, said hinge comprising a one way operation for the solenoid impulse but allowing of a manual operation thereof independently of the solenoid. 40 45 50 55 60 65

13. A multiple high intensity arc projector including a plurality of elliptical reflecting focusing mirrors, the arcs including carbons positioned at the focal points of one mirror and mounted on a support projecting through an opening in the center of the mirror, said support comprising a tube and carbon supporting and feed means mounted in conjunction with the tube, the negative carbon feed positioned outside the tube and the positive carbon feed drive extending inside 75

- the tube to the outer end thereof, automatic means for striking the arc between the carbons, said automatic means including a solenoid in the current carrying circuit for the arcs, a system of levers connected with the solenoid for feeding the negative carbons forwardly into contact with the positive carbons upon closing of said circuit, and a manually operated arc striking element in conjunction with said automatically operated mechanism, said manually-operated mechanism, said manually-operated arc striking element comprising a hinged connection in the solenoidally operated lever, said hinge comprising a one way operation for the solenoid impulse but allowing of a manual operation thereof independently of the solenoid, together with the resilient means for automatically returning the negative carbon to proper arc maintaining position after the arc is struck.
14. In a carbon arc lamp, means for instantaneously releasing the carbons, said means comprising a spring-impelled carbon gripping element, said carbon gripping means including automatic feed means for the carbons, said automatic feed means comprising a drive shaft, knurled feed wheels for the carbons and gear connections between the drive shaft and the knurled feed wheels, and current-carrying electrodes for the carbons, said electrodes being formed of laterally separable parts mounted adjacent to and operable with the carbon gripping and releasing means, and pin and socket connections between the carbon gripping and releasing means and said electrodes.
15. In a carbon arc lamp, means for instantaneously releasing and replacing the carbons, said means comprising a spring-impelled carbon gripping and positioning element, said carbon gripping and positioning means including automatic feed means for the carbons, said automatic feed means comprising a drive shaft, knurled feed wheels for the carbons and gear connections between the drive shaft and the knurled feed wheels, and current-carrying electrodes being formed of laterally separable parts for the carbons, said electrodes mounted adjacent to and operable with the carbon gripping and releasing means, and pin and socket connections between the carbon gripping and releasing means and said electrodes, said pin and socket connections including provision for lost motion between the electrodes and the carbon gripping elements.
16. A multiple high intensity arc projector including a casing, an elliptical reflecting focusing mirror, the arcs including carbons positioned at the focal points of the mirror and mounted on a support projecting through an opening in the center of the mirror, said support comprising a tube and carbon supporting and feed means mounted in conjunction with the tube, the negative carbon feed positioned outside the tube and the positive carbon feed drive extending inside the tube to the outer end thereof, and automatic means for striking the arc between the carbons, said automatic means including a solenoid in the current carrying circuit for the arcs, and a system of levers connected with the solenoid for feeding the negative carbons forwardly into contact with the positive carbons upon closing of said circuit, and a manually operated arc striking element in conjunction with said automatically operated mechanism, said manually-operated arc striking element comprising a hinged connection in the solenoidally operated lever, said hinge comprising a one way operation for the solenoid impulse but allowing of a manual operation thereof independently of the solenoid, together with resilient means for automatically returning the negative carbon to proper arc maintaining position after the arc is struck, the entire mirror and carbon assembly being slidable forwardly and rearwardly as a whole from the casing.
17. A multiple high intensity arc projector including a casing, an elliptical reflecting focusing mirror, the arcs including carbons positioned at the focal points of the mirror and mounted on a support projecting through an opening in the center of the mirror, said support comprising a tube and carbon supporting and feed means mounted in conjunction with the tube, the negative carbon feed positioned outside the tube and the positive carbon feed drive extending inside the tube to the outer end thereof, and automatic means for striking the arc between the carbons, said automatic means including a solenoid in the current carrying circuit for the arcs, and a system of levers connected with the solenoid for feeding the negative carbons forwardly into contact with the positive carbons upon closing of said circuit, and a manually operated arc striking element in conjunction with said automatically operated mechanism, said manually-operated arc striking element comprising a hinged connection in the solenoidally operated lever, said hinge comprising a one way operation for the solenoid impulse but allowing of a manual operation thereof independently of the solenoid, together with resilient means for automatically returning the negative carbon to proper arc maintaining position after the arc is struck, the entire mirror and carbon assembly being slidable forwardly and rearwardly as a whole from the casing, and water-cooling means for the mirror.

FREDERICK A. BERG.
